UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,565, dated November 18, 1884.

Application filed September 12, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,411;) and I do hereby declare that the engraved prints accompanying this specification convey to any one accustomed to using paper patterns a clear understanding of how to a garment made up by the pattern will appear.

The design shows a round walking-skirt and an overdress. The skirt displays a deep lower front-drapery exhibiting draping plaits in its back edges, and separating at the center some distance below the top in two deep points that fall nearly to the bottom; a shorter upper front-drapery exhibiting draping plaits in its center and back edges and rounding away from the plaits at the center. The overdress dis-

plays a closely-fitted basque-front shaping a point at the lower end of the closing and a high arch over the hips. A closely-fitted polonaise-back that exhibits under-folded plaits at the lower ends of its body-seams descends in straight folds nearly to the bottom at the center, and exhibits a deep loop and end at each side of its drapery; coat-sleeves, and a standing collar.

What I claim as my invention, and desire to secure by Letters Patent, is—

The design for a lady's costume, as shown in the engraved prints accompanying this specification.

SARAH JANE SHIELS.
